TURBINE DRAFT TUBE

Howard L. Cooper, Portland, Oreg.

Application March 5, 1935, Serial No. 9,439

4 Claims. (Cl. 253—117)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates in general to the art of regaining some of the residual velocity head in the water, lost upon leaving the hydraulic turbine in a form of increased efficiency of the hydraulic turbine. It is a well recognized fact that on 10 account of the function which is fulfilled by the draft tube, it is properly regarded as an integral part of the turbine. Therefore, considering the turbine and draft tube as a unit, it may be seen that the less the kinetic energy lost through the 15 tube, the higher the efficiency of the wheel.

The total power available is that due to the total head from head water level to tail water level. The power of the turbine is less than this by an amount equal to that lost in the intake, pen- 20 stock, draft tube, mechanical friction and hydraulic loss. Anything which reduces the loss outside the turbine adds just that much more to the power which the water can give up within the turbine.

25 Further, the total energy remaining in the water at the runner end of the draft tube depends not only upon the elevation of this point above or below the tail water level but also upon the velocity head of the water at that section minus the friction and hydraulic losses to be lost within the draft tube, including the residual velocity head at its discharge. The less these losses, the higher the available energy at the runner, the better will be its performance.

30 Among the causes contributing to low efficiencies of the usual elbow or horizontal types of draft tube are the following:

Failure to divide water evenly in horizontal discharge channels.

40 Water leaving turbine runner with an induced whirl which continues to the end of the draft tube, causing air pockets, surging and uneven velocities.

The primary object of my invention is to trans- 45 fer the flow in the draft tube from a turbulent, whirling flow to a smooth, straight flow nearly parallel to the draft tube walls.

A further object of my invention is to accom- 50 plish this change in flow within the shortest distance possible.

A still further object is to regulate the flow in my draft tube so that resistance to flow is a minimum with the results of a more efficient turbine operation.

55 Another object is to produce a draft tube of

such form that its length may be materially reduced without affecting its efficiency.

I attain these objects by shaping the draft tube walls as illustrated in the accompanying drawings in which:—

Fig. 1 is a vertical cross-section through the draft tube and

Fig. 2 shows a section taken through the draft tube on the line 2—2 of Fig. 1 with turbine blades omitted:

Fig. 3 shows a section taken through the draft tube on the line 3—3 of Fig. 1, where tube is beginning to assume a bulbous contour;

Fig. 4 shows a section taken through the draft tube on line 4—4 of Fig. 1, in which view an elongation of the bulbous portion is shown;

Fig. 5 shows a section taken through the draft tube on the line 5—5, here the bulbous sections have been elongated still further and a section of a centrally located pier which divides the draft tube into two conduits, is shown;

Fig. 6 shows a section taken through the draft tube on the line 6—6. In this locality the separated conduits are assuming a rectangular shape of greater cross-sectional area than those shown in Fig. 5;

Fig. 7 shows a section taken through the draft tube on the line 7—7. In this view the separate conduits have been increased in area and are square in shape;

Fig. 8 is a section taken on the line 8—8 and shows the inner edge of the centrally located pier which divides the outlet portion of the tube into two conduits.

Similar numerals refer to similar parts throughout the several views.

Any turbine runner, running in counter-clockwise direction gives to the fluid a counter-clockwise whirling component as it discharges from the runner into section 2—2.

The bulbous portions of the turbine draft tube from section 2—2 to 3—3 serve as collecting channels, in which much of the whirling or rotating motion is dissipated and the flow partially straightened.

From section 3—3 to 4—4 the change from a rotating motion to a straight line flow has nearly been completed.

Any turbine runner, running in a clockwise direction with a clockwise whirling component, will have similar but opposite-hand collecting channels.

The drawings are shown for counter-clockwise operation of the runner.

The draft tube as shown in the illustration

may be considered as made up of three portions; an intake portion, an elbow, and an outlet portion. The contour of the intersection of said tube with a vertical plane passed through its central axis 5 outlines lateral boundaries of the interior surface of said tube which gradually converge from the inlet opening at section 2—2 to the elbow, and gradually diverge from the elbow to the outlet opening, adjacent section 7—7 as shown in 10 Fig. 1, and the contour of the intersection of said tube with a plane passed through the central axis normal to said first mentioned vertical plane, would outline lateral boundaries of the internal surface of said tube which gradually diverge from 15 the inlet to the outlet opening, as indicated by the sectional views illustrated in Figs. 2 to 7 inclusive. From about the center of the elbow a vertically disposed central pier (10) divides the tube in two separate conduits. Throughout the 20 entire length of the tube from the inlet opening to the outlet opening the cross-sectional contour of the interior surface is as follows: In the inlet portion of the tube which extends from the sections 2—2 shown in Fig. 2 to the section 4—4 25 shown in Fig. 4 the tube gradually changes its contour from a circular form in the vicinity of the turbine blades to an elongated form with a restricted center and bulbous extremities, forming collecting channels 12 and 12' on either side of 30 the restricted central portion. The bulbous contour, indicated throughout the various views by the numerals 11 and 11', is more pronounced in the direction of the flow, which is indicated by the arrows. This contour continues throughout 35 the elbow wherein the central pier (10) (Fig. 8) is formed, said pier continuing as a partition wall throughout the outlet portion of the draft tube and dividing the collecting channels 12 and 12' into two separate conduits. Within the separate 40 conduits the bulbous contour becomes less and less pronounced as the interior of the conduits assume a rectangular shape, as shown in the sectional view in Figures 5 to 7 inclusive.

Throughout the entire length of the draft tube 45 the direction of the particles or molecules of the fluid stream is gradually changed from a circular whirling motion at the inlet opening to a longitudinal movement at the outlet.

Having described my invention what I claim as 50 new and wish to secure by Letters Patent is:—

1. A turbine draft tube adapted for the reception of fluid in a whirling stream, and means interior said tube comprising diametrically opposite collecting channels of bulbous cross-sectional

contour, said contour being accentuated in the direction of flow, adapted to progressively change the rotative movement of the fluid to a straight line flow.

2. A turbine draft tube comprising, an inlet 5 portion, an outlet portion, and an intermediate elbow, a centrally disposed pier dividing said outlet portion into separate conduits, and means interior said tube comprising diametrically opposite collecting channels of bulbous contour extending from the inlet portion into the outlet portion, adapted to progressively change rotary motion of a fluid passing therethrough into a straight line flow.

3. A turbine draft tube comprising an inlet 15 portion, an outlet portion and an intermediate elbow, means in connection with the inner surface of the bore of said tube adapted to convert the rotary movement of the fluid passing through the tube into a direct line flow, the conversion 20 being effected within a limited area between the inlet and outlet openings of the tube, said means comprising laterally disposed collecting channels 25 of bulbous contour located on either side of a restricted central portion, extending within the 30 inlet portion, the elbow and the outlet portions of said tube.

4. A turbine draft tube composed of an inlet portion, an outlet portion, and an intermediate elbow, the contour of the intersection of said tube 35 with a vertical plane passed through its central axis outlining boundaries of the interior surface of said tube which gradually converge from the inlet opening to the elbow, and gradually diverge from the elbow to the outlet opening, and the 40 contour of the intersection of said tube with a plane passed through the central axis normal to said first mentioned plane, outlining boundaries of the internal surface of said tube which gradually diverge from the inlet to the outlet opening; a central vertically disposed pier extending from the elbow to the outlet opening, dividing the 45 outlet portion of the tube into separate conduits, the interior contour of the tube from the inlet opening to the pier being formed with gradually enlarging bulbous channels on each side of a constricted central portion, and from the beginning of the pier to the outlet opening separate conduits in which the channels of bulbous contour 50 are continued, their contour becoming less pronounced as the conduits approach their outlets.

HOWARD L. COOPER.
